CLAIM

The ornamental design for a mini nail UV lamp, as shown and described.

DESCRIPTION

FIG. 1 is a perspective view of a mini nail UV lamp showing my new design;

FIG. 2 is a front elevational view thereof;

FIG. 3 is a back elevational view thereof;

FIG. 4 is a right-side elevational view thereof;

FIG. 5 is a left-side elevational view thereof;

FIG. 6 is a top plan view thereof;

FIG. 7 is a bottom plan view thereof; and,

FIG. 8 is a perspective view of the mini nail UV lamp with unfolded legs.

The broken lines in the drawings depict part of the mini nail UV lamp that form no part of the claimed design.

1 Claim, 8 Drawing Sheets
